Margaret Cunningham ^{INVENTOR}
BY
Jno. L. Thaxter ^{ATTORNEY.}

UNITED STATES PATENT OFFICE.

MARGARET CUNNINGHAM, OF PHILADELPHIA, PENNSYLVANIA.

DESIGN FOR A NECKTIE-HOLDER.

SPECIFICATION forming part of Design No. 30,755, dated May 16, 1899.

Application filed February 27, 1899. Serial No. 707,088. Term of patent 7 years.

To all whom it may concern:

Be it known that I, MARGARET CUNNINGHAM, a citizen of the United States, residing at Philadelphia, county of Philadelphia, and 5 State of Pennsylvania, have invented and produced a new and original Design for Necktie-Holders, of which the following is a specification, reference being had to the accompanying drawings, forming part thereof.

10 Figure 1 is a front view of a necktie-holder, showing my design. Fig. 2 is a section view of the same on the lines $\alpha\alpha$ of Fig. 1.

D is a rectangular-shaped plate.

15 A is a recess in the upper long side of the plate, said recess having parallel straight sides and its inner end curved.

B B are strips of the plate D, formed of parallel slits in said plate. These strips are raised from the body of the plate, so as to partake of the arch shape shown in Fig. 2. 20

Having thus described my invention, what I claim as new, and desire to secure by Letters Patent, is—

The design for a necktie-holder as herein shown and described.

MARGARET CUNNINGHAM.
